UNITED STATES PATENT OFFICE.

SAM H. VINNER, OF BILLINGS, MONTANA.

NUT LOCK.

Application filed March 18, 1924. Serial No. 700,156.

To all whom it may concern:

Be it known that I, SAM H. VINNER, a citizen of the United States, residing at Billings, in the county of Yellowstone and 5 State of Montana, have invented certain new and useful Improvements in Nut Locks, of which the following is a specification.

The present invention relates to nut locks and aims to provide a device of this nature 10 having a simple and efficient construction, one which is reliable, easy to manipulate, comparatively inexpensive to manufacture, and well adapted to the purpose for which it is designed.

Another important object of the invention 15 is to provide a nut lock which will take the place of the ordinary type using a cotter pin allowing the lock to be quickly handled.

With the above and numerous other objects in view as will appear as the description progresses, the invention resides in 20 certain novel features of construction, and in the combination and arrangement of 25 parts as will be hereinafter more fully described and claimed.

In the drawing,

Figure 1 is a top plan view of a bolt and 30 nut showing my lock associated therewith,

Figure 2 is a section therethrough,

Figure 3 is an elevation thereof,

Figure 4 is a perspective view of the lock,

Figure 5 is a section showing a modified 35 form of the lock, and

Figure 6 is a detail perspective of the modified form of the lock.

Referring to the drawing in detail it will be seen that the bolt 1 is provided with an end slot 2 in which is pivoted a locking 40 member 3. The nut 4 is provided with a series of dovetailed notches 5 on its upper or outer face that is the bottoms of these notches are wider than the tops. The lock 3 shown in Figures 1 to 4 inclusive is formed

45 of spring sheet metal and is substantially U-shaped in cross section the body 6 thereof being provided with registering apertures 7 for receiving a pin 8 spanning an intermediate portion of the slot 2 so as to pivotally mount the lock. An arm 9 extends from

the body and is constructed with the two normally diverging lips 10. As the lock is pivoted so that the arm enters one of the notches 5 the lips 10 may be pressed toward each other so that they may enter the top 55 of the notches and by the use of a hammer or any other handy tool this arm may be then given a blow so that the lips may be positioned substantially as shown in Figure 3 thus preventing accidental displacement of 60 the lock from the notch in which it is positioned. A series of recesses 12 one registering with each notch 5 allows the body 3 of the lock to rotate freely.

In Figures 5 and 6 the lock 3' includes a 65 body 4' of solid construction having the arm 5' also of solid construction extending therefrom. The body 4' is provided with the aperture 7' so that the pin 8 may pass therethrough for pivotally mounting the 70 lock within the slot 2.

Although I have described my invention with a certain degree of particularity, it is to be understood that numerous changes in the details of construction and in the combination and arrangement of parts may be resorted to without departing from the spirit of the invention hereinafter claimed or sacrificing any of its advantages. 75

Having thus described my invention, what 80 I claim as new is:

1. In combination, a bolt provided with an end slot, a lock pivotally mounted in said slot, said lock including a substantially U-shaped formation having a body and an arm 85 extended therefrom, said arm being formed with a pair of diverging lips, and a nut threaded on the bolt and provided on its outer face with a series of notches of dovetailed formation for the reception of the 90 arm of the lock so that the lips thereof will hold the arm in the notch in which it is positioned so as to prevent accidental displacement thereof.

2. In combination, a bolt provided with 95 an end slot, a lock pivotally mounted in said slot, said lock including a substantially U-shaped formation having a body and an arm extended therefrom, said arm being formed with a pair of diverging lips, a nut threaded 100

on the bolt and provided on its outer face with a series of notches of dovetailed formation for the reception of the arm of the lock so that the lips thereof will hold the arm in the notch in which it is positioned so as to prevent accidental displacement thereof, the interior of said nut provided with recesses one registering with each notch for

allowing the body of the lock to pivot freely.
In testimony whereof I affix my signature ¹⁰
in presence of two witnesses.

SAM H. VINNER.
